US00D857716S

(12) **United States Design Patent** (10) Patent No.: **US D857,716 S**
Zimmerman et al. (45) Date of Patent: **** Aug. 27, 2019**

(54) **THERMAL CYCLER DISPLAY SCREEN
WITH GRAPHICAL USER INTERFACE**

(71) Applicant: **LIFE TECHNOLOGIES
CORPORATION**, Carlsbad, CA (US)

(72) Inventors: **Sean Zimmerman**, San Diego, CA (US); **Scott Rickes**, San Diego, CA (US); **Joseph Lee**, San Diego, CA (US); **Michael Joseph Jackson**, Carlsbad, CA (US)

(73) Assignee: **LIFE TECHNOLOGIES
CORPORATION**, Carlsbad, CA (US)

(**) Term: **15 Years**

(21) Appl. No.: **29/597,551**

(22) Filed: **Mar. 17, 2017**

Related U.S. Application Data

(62) Division of application No. 29/555,513, filed on Feb. 23, 2016, now Pat. No. Des. 785,025, which is a division of application No. 29/445,006, filed on Feb. 6, 2013, now Pat. No. Des. 753,685.

CLAIM

The ornamental design for a thermal cycler display screen with graphical user interface, as shown and described.

DESCRIPTION

THE FIGURE is a front view of a thermal cycler display screen with graphical user interface showing our new design.

The portions of the display screen, text, and other features depicted in broken lines are not part of the claimed design.
